(57) **CLAIM**

I claim the ornamental design for a combination portable toilet and baby diaper changing table, as shown and described.

DESCRIPTION

FIG. 1 is a front, left side and top exploded perspective view of the combination portable toilet and baby diaper changing table, showing the seat back in the down position;

FIG. 2 is a front, left side and top exploded perspective view of the combination portable toilet and baby diaper changing table, showing the seat back in the down position;

FIG. 3 is a front, top and left side view of the combination portable toilet and baby diaper changing table, showing the seat back in the upright position;

FIG. 4 is a front, top and left side view of the combination portable toilet and baby diaper changing table, showing the seat back in the folded position;

FIG. 5 is a left side elevational view of the combination portable toilet and baby diaper changing table, showing the seat back in the folded position;

FIG. 6 is a top plan view of the combination portable toilet and baby diaper changing table, showing the seat back in the folded position;

FIG. 7 is a right side elevational view of the combination portable toilet and baby diaper changing table, showing the seat back in the folded position;

FIG. 8 is a front elevational view of the combination portable toilet and baby diaper changing table, showing the seat back in the folded position;

FIG. 9 is a bottom plan view of the combination portable toilet and baby diaper changing table, showing the seat back in the folded position; and,

FIG. 10 is a rear elevational view of the combination portable toilet and baby diaper changing table, showing the seat back in the folded position.

The broken line showing of environment in FIG. 1 is included for the purpose of illustration only and forms no part of the claimed design.
